[45] Date of Patent: **Mar. 31, 1998

[54] ICE-SKATING BLADE

4,805,934 2/1989 Mullenax 280/87.042
5,411,320 5/1995 Alderman et al. 301/5.3

[76] Inventor: Linda Priester, P.O. Box 11,
Massapequa Park, N.Y. 11762

Primary Examiner—Raphael Barkai
Attorney, Agent, or Firm—Myron Amer P.C.

[**] Term: 14 Years

[57] CLAIM

[21] Appl. No.: 71,462

The ornamental design for ice-skating blade, as shown and
described.

[22] Filed: May 27, 1997

DESCRIPTION

[51] LOC (6) Cl. 21-02

FIG. 1 is side elevational view of an ice-skating blade
showing my new design;

[52] U.S. Cl. D21/225

FIG. 2 is a front elevational view taken along the line 2—2
of FIG. 1; and,

[58] Field of Search D21/224-231;

FIG. 3 is a side elevational view thereof; the side opposite
being identical.

280/11.18, 11.2, 11.19, 11.22, 811, 87.042;
301/5.3

The broken line showing of the skate and frame in FIGS. 1
and 2 is for illustrative purposes only and forms no part of the
claimed design.
